(57) **CLAIM**

The ornamental design for a storage table, as shown and described.

DESCRIPTION

FIG. 1 is a rear, left and top perspective view of a storage table showing my new design;
FIG. 2 is a front, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is a partial enlarged view of a portion 9 shown in FIG. 1;

FIG. 10 is a partial enlarged view of a portion 10 shown in FIG. 1;
FIG. 11 is a partial enlarged view of a portion 11 shown in FIG. 2; and,
FIG. 12 is a partial enlarged view of a portion 12 shown in FIG. 2.

The broken lines depict portions of the storage table that form no part of the claimed design.

1 Claim, 12 Drawing Sheets
